UNITED STATES PATENT OFFICE.

JAMES R. MOFFATT, OF CHICAGO, ILLINOIS, ASSIGNOR TO UNION
SPECIAL SEWING MACHINE COMPANY, OF CHICAGO, ILLINOIS,
A CORPORATION OF ILLINOIS.

BAND OR TAPE GUIDING DEVICE FOR SEWING-MACHINES.

No. 836,198.

Specification of Letters Patent.

Patented Nov. 20, 1906.

Application filed April 7, 1904. Serial No. 202,046.

To all whom it may concern:

Be it known that I, JAMES R. MOFFATT, a citizen of the United States, residing at Chicago, in the county of Cook, State of Illinois, have invented certain new and useful Improvements in Band or Tape Guiding Devices for Sewing-Machines, of which the following is a description, reference being had to the accompanying drawings, and to the letters of reference marked thereon.

My invention relates to an improvement in devices for guiding tape or other strips or bands to be sewed to a body material to the stitch-forming mechanism of the machine, the object being to provide an adjustable guide therefor which can be adjusted for various widths of tapes, bands, or strips or which can be set to properly guide those tapes, bands, or strips which are made of such material as to be narrowed up materially under the strain placed upon them when being fed into the machine.

The invention is herein shown as embodied in a tape-guiding presser-foot; but it will be understood that I do not wish to be thus limited, as the features forming the subject-matter of the invention may be applied to guides attached to the throat-plate, bed-plate, or any other suitable supporting part in the sewing-machine.

The invention consists in the matters hereinafter described, and referred to in the appended claims.

In the accompanying drawings, which illustrate the invention, Figure 1 represents a perspective view of a presser-foot embodying my invention, showing the parts in one position. Fig. 2 is a similar view showing the parts in a different position. Fig. 3 is a detail view showing the parts all detached.

In the drawings, A represents the presser-foot, having the usual needle-openings a and having the inclined upwardly-projecting toe-piece a', which is provided with the projecting stud b, internally screw-threaded.

B and C represent the two side pieces of the tape-guide, which embraces the sides of the toe-piece a' and having interlapping horizontal portions c d, which are guided by the projection in top of the toe-piece, one of the horizontal portions c being slotted to engage said projection, and as the parts c and d interlap they will be guided by the projec-

tion as they are adjusted toward and from each other. One of the side pieces B has also secured to it a pin e, which passes through an opening in the other side piece C. This pin forms a guide for the tape in passing from the reel to the tape-guide and is of length sufficient to project beyond the guiding edge C to form a bearing when the side pieces are adjusted to their extreme position. A thumb-lever E is pivoted on the screw f, which screw passes into the threaded stud b and holds the parts together, a washer g being provided. Said lever E has oppositely-extending slots F, engaging pins h on the parts B C, so that by swinging the lever the side pieces B and C will be adjusted toward and from each other.

Having thus described my invention, what I claim, and desire to secure by Letters Patent, is—

1. A guiding device for tape, bands or like material, having a support, a projection on said support, guides for the sides of said material, and interlapping plates carried by said guides and embracing said projection, means for holding the plates from vertical movement and means for simultaneously adjusting said guides laterally.

2. A guiding device for tape, bands or other material having a support, a projection thereon, side guides for the tape or other material, having interlapping longitudinal plates embracing said projection, a screw engaging said projection and holding the plates in place, and means for simultaneously adjusting the plates laterally; substantially as described.

3. A guiding device for tape, bands or other like material having a support, a projection thereon, side guides for the tape or other material having interlapping longitudinal plates embracing said projection, a screw engaging said projection and holding the plates in place and a lever pivoted on said screw and having parallel slots engaging pins or projections on the plates; substantially as described.

4. A guiding device for tape, bands or other like material having a support, a projection thereon, side guides for the tape or other material having interlapping longitudinal plates embracing said projection, a screw engaging said projection and holding the plates in place and means for adjusting

the plates, and a guiding-pin for the tape, extending between the side guides, engaging one, and passing through the other; substantially as described.

- 5 5. A tape or strip guiding presser-foot having the extending toe portion with guiding-flanges for the material, interlapping longitudinal plates supported on said extending toe portion, means for holding said plates from 10 vertical movement, a guiding-pin for the tape extending between the side guides en-

gaging one of them and passing through the other and means for simultaneously adjusting the side guides toward and from each other, substantially as described.

In testimony whereof I affix my signature in presence of two witnesses.

JAMES R. MOFFATT.
